their Atty.

UNITED STATES PATENT OFFICE.

WILLIAM J. TOWLES, EUGENE L. TOWLES, AND GEORGE M. TOWLES, OF LOS ANGELES, CALIFORNIA.

WATER HEATER.

Application filed December 22, 1924. Serial No. 757,425.

This invention relates to water heaters, and in particular to the water coils of so-called instantaneous heaters.

One of the objects of this invention is to construct a heater so that the water flows through several distinct though interconnected coils.

Another object is to arrange distinct though interconnected coils so that water must repeatedly come in touch with the heating medium such as a flame from a burner while passing through the several coils.

Another object is to provide coils wound of cylindrical or conical cores of different sizes so that each larger coil may surround a smaller, regardless of whether the coils are wound in a cylindrical or conical form.

Another object is to provide several cylindrical and conical coils disposed one within the other, and another coil wound in a flat form to be disposed below the several other coils, all the several coils to be in one continuous communication from the inlet to the outlet.

Other objects will appear from the following description and appended claims as well as from the accompanying drawing, in which the figure is a somewhat diagrammatical illustration in a vertical plane, partly in side elevation, and partly in vertical mid-sectioinal view, of a portion of a water heater.

From a technical standpoint it is desirable that the water is directed in a direction contrary to the direction of the passing of the products of a heating medium. In particular, if a gas burner or a heating medium with an open flame is used, the heat is normally most intense near the flame while it gradually decreases in heating properties at points further away from the flame. Whether the flame is directed up and down or in various directions is immaterial. The most intense heat is normally always close to the source of the heat producing element, while less intense heat is at points more distant from such heat producing element, whether the most intensely heated points are at a higher or lower level, or whether the less intensely heated points are at a higher or lower level, is immaterial. A heating of water can be most efficiently accomplished by directing the water in the opposite di-

rection of the heat issuing from any heat producing element.

A simple arrangement in a heater is illustrated. A burner is outlined at 3, above which a number of coils are arranged. Assuming that gas is used in the burner, the products of combustion normally pass upwardly around the coils towards the top. The most intense heat is therefore developed just above the burner 3 near the lower terminations of the coils at the point indicated, at 4, while less intense heat can be expected near the upper termination of the coils at the point indicated at 5, the heat-force of the products of combustion from the burner 3 naturally decreasing as it passes around the coils upwardly.

To accomplish a most efficient heating of water in the several coils, as suggested above, the water is preferably passed or directed from the upper individual windings in the several coils in a downward direction, through the lower windings of such coils.

The term "winding" or "windings" will hereafter be used in this application to indicate one coil or winding in the several distinct coils, and the term "coil" will hereafter only be used for the several structures each embodying several windings.

One coil is illustrated of conical form with the wider winding at the bottom, as indicated at 6, and the narrower winding at the top, as indicated at 7. A second coil is illustrated as of cylindrical form, as indicated at 8. A third distinct coil is illustrated as of conical form, with the wider winding at the top, as is indicated at 9, and having the narrower winding at the bottom, as indicated at 10. A fourth distinct coil is illustrated as of flat form extending practically over the whole area below all the other coils, as indicated at 11.

All these four distinct coils are interconnected so that a continuous communication is maintained through the several coils between a water inlet, indicated at 12, and a water outlet, indicated at 13. A portion of a housing is indicated at 14, to inclose all the coils and the burner so that the products of combustion or the heating-force may be forced to surround the several coils in an upward direction.

The inlet is shown as being in communica-

tion with the lower winding 6 of the larger or outer conical coil 15. This manner of connecting the heater has been established with some heaters, but it will easily be understood that the water inlet may communicate first with the upper winding 7 of the coil 15, if not straight across through the housing 14, depending entirely on existing conditions in a heater or a heater casing to provide the most practical construction in individual or particular cases as they occur in the practice when this invention is applied to already existing heaters.

The upper winding 7 is in communication 15 with the upper winding 17, as indicated at 18. The lowermost winding 19 of the coil 8 is in communication with the uppermost winding 20 of the inner conical coil 21 through an extra winding 22. The lowermost winding 10 of the coil 21 is in communication with the coil 11, as indicated at 23. The flat coil 11 is in communication with the water outlet, as indicated at 24. Under this arrangement water passes through coil 25 8 in a downward direction contrary to the movements of the products of combustion in this type of water heater. By providing the extra short-cut winding 22 between the lower winding 19 of the coil 8 and the upper winding 9 of the coil 21 at 20, water is also directed to pass through the coil 21 in a downward direction contrary to the upward passing of the products of combustion from the burner 3. The flat coil 11 in the structure 35 serves to pass the water, so far already heated in the several coils, for the whole length of coil 11 through the highest-heated level or strata in the heater directly over the burner 3.

Against this form it might be argued that 40 the outer coil 15 is not used to the fullest extent since the water must pass in an upward direction through this coil 15 from the lower winding 6 to the upper winding 7, thereby practically following the heating medium, as the products of combustion from the burner 3, in such upward direction. It 45 may be said that the lower winding 6 of coil 15 is subjected to the greater heating force of the products of combustion, and, as the heating force of the products of combustion decreases while the products of combustion pass upwardly, the upper windings of the coil 15 are disposed so that the water passing through such coils could not very well receive material heating over the heating received in the lower coil 6.

In heaters that allow an inlet pipe 50 straight across from the upper winding 7 through the housing 14 in a similar manner as indicated at 12 in connection with the lower winding 6, such a straight connection may be preferable.

The lower coil 11 serves always as a final

heating coil for the three-fold heated water 65 from the other three coils.

It must be understood that the coils are illustrated in the drawing of different length merely for the purpose of giving a clear understanding of the interconnection of the 70 several coils, and that the coils may be of equal length, or the inner coil may be longer than the outer coils, so that all coils terminate in their upper ends in the same level, or the coils may be of different length in an 75 entirely different manner.

Having thus described our invention, we claim:

1. In a water heater, a conical water coil disposed with its wider winding at the bottom and with the narrower winding at the top and provided with a cool water supply connection, a second coil with windings in a cylindrical form having communication with the first coil, a third coil of conical form 85 with the wider winding disposed at the top and the narrower winding at the bottom having communication with the second-named coil, the cylindrical coil being disposed between the two conical coils so as to 90 form two comparatively equal passages on both sides of the cylindrical coil wider at the bottom and narrower at the top so as to assure an even heating of the central cylindrical coil, and a flat coil disposed transversely below the other three coils having 95 communication with the last-named coil and forming the water outlet of this coil system.

2. In a water heater, a conical water coil disposed with its wider winding at the bottom and with the narrower winding at the top and provided with a cool water supply connection, a second coil with windings in a cylindrical form having communication with the first coil, a third coil of conical form 100 having communication with the second-named coil and being disposed with the wider winding at the top and the narrower winding at the bottom, the cylindrical coil being disposed between the two conical coils 105 so as to form two comparatively equal passages on both sides of the cylindrical coil wider at the bottom and narrower at the top so as to assure an even heating of the central cylindrical coil, a short-cut communicating pipe between the lowermost winding of the second and the uppermost winding of the third-named coil, and a flat coil disposed transversely below the other three coils 110 having communication with the third-named coil and forming the water outlet of 115 this coil system.

In testimony that we claim the foregoing as our invention we have signed our names.
